1,955,041

SIMULTANEOUS TREATMENT OF CRUDE
PETROLEUMS OR THE LIKE AND BITUMI-
NOUS COALS OR THE LIKE

Francis S. Woidich, Tulsa, Okla.

Application March 3, 1932, Serial No. 596,608
In Germany January 4, 1932

7 Claims. (Cl. 196—56)

This invention relates to a process and apparatus for obtaining anti-knock motor fuel and oils of high calorific value with a high percentage of finely divided carbon, from liquid fuels such as mineral oil, tar oil, gas oil, heating oil, shale oil and the like, and also from solid fuels with a high percentage of volatile bitumen hydrocarbon constituents, such as gas coal, gas flame coal, cannel coal, lignite and the like.

10 The process is carried out by introducing the finely ground coal into the liquid fuel and making an emulsion of coal and oil, with optional heating of the mixture, in stirring mechanisms, which for this purpose may be provided with 15 a heating jacket. The emulsion accruing from the stirring mechanisms is now further heated, under a pressure varying according to the operating conditions, to a predetermined temperature, and then passed into a separator, in which 20 at the same time its pressure is partially reduced.

The more volatile constituents of the liquid and solid fuel is now distilled off, and then 25 passed into a rectifying and fractionating plant, in which they are worked up to different fractions. The constituents not distilled off in the separator are passed first over a distillation and re-action column R. T. into a converter, in which in a hydrogenous atmosphere and under definite 30 conditions of pressure and temperature, a selective building up and disintegrating process proceeds, so that further constituents of higher boiling points are converted into more volatile constituents, while a residual oil remains, having a high percentage of very finely divided carbon, which can be burnt in furnaces of any kind 35 as a high grade fuel of high calorific value.

As compared with the low temperature distillation of bituminous coals, the process according to this invention has the advantage that 40 the bituminous hydrocarbons, in the course of the heating under pressure, go into solution in the suspending oil, so that they are protected against pyrogenic decomposition, which, in the usual low temperature distillation processes results in a reduction of the yield of light motor 45 fuel, with corresponding increase of the proportion of permanent gases, phenols, and homologues, as well as of pitch.

The efficiency of the process is also increased 50 because the emulsion is a good conductor of heat, in proportion to the solid coal, so that the process can be carried out at lower temperatures and more rapidly than is the case with the usual low temperature distillation processes.

55 In addition to this, the temperatures at which

the bituminous hydrocarbons of the coal evaporate are lower than in the ordinary low temperature distillation process, in consequence of the high solution pressure of the bituminous hydrocarbons, as compared with the suspending 60 and solvent oil, and of the increased vaporization pressure of the hydrocarbons of the solvent oil.

Simultaneously with the decomposition and the dissolving of the carbon bitumen in the 65 suspending oil, there also occurs an extensive comminution of the fine particles of coal, so that as a result hereof they distribute themselves in the residual oil in colloidal form, whereby a new homogeneous and stable fuel-oil product 70 is obtained, which may be designated "Carbonol".

This product contains about 50 percent. of residual oil of low viscosity and 50 percent. of 75 colloidally distributed carbon, and may be regarded as a refined product of the oil and coal.

Since however this mixture "Carbonol" is heavier than water, and is neither soluble in, or 80 miscible with water, it can be stored under water for the purpose of obviating any risk of fire.

Under these circumstances the formation of explosive gaseous mixtures in storage is precluded.

For heating purposes it admits of being atomized just as well as the fuel oil at present used.

Its combustion is effected entirely without 85 noise, as contrasted with the combustion of fuel oil. This yields a short and luminous flame, whereby the transmission is promoted of heat by radiation, which in modern operations is being more and more sought after.

The good combustion properties of the carbonol also yield the possibility of burning with a lower excess of air, whereby the efficiency of the furnace plant is raised.

Finally in addition to this, under the same conditions, the quantity of steam or energy required for atomization is lower than when ordinary heating oil is employed.

Besides this high grade heating-oil product, 100 there is obtained, on the other hand, a highly knock-proof motor fuel from the combination of the highly knock-proof bituminous hydrocarbons of the coal with the less knock-proof hydrocarbons of the direct distillation of the suspending 105 oil and the knock-proof hydrocarbons of the suspending oil cracking process, which is a selective, building up and breaking down process that occurs under special conditions.

This highly knock-proof motor oil, and is sub- 110

divided according to its constitution and the purpose for which it is to be used into the various fractions "Bituminol I", "Bituminol II", "Bituminol III" and so forth.

5. Of these fractions, the light one may be employed in aircraft motors, the medium one in ordinary motors, and the heavy one in Diesel motors.

These "Bituminols" are high grade refinement products of the bituminous coal and the mineral oils, which, in the same range of boiling point, exhibit a greater storage stability, as regards losses and resinification, and enable motors to be easily started and easily accelerated.

10. Since the products themselves are very knock-proof, they can, by mixing them with fuels that are not knock-proof, convert the latter into anti-knock fuels with a sufficiently high anti-knock coefficient.

15. According to the process of manufacture these products consist of distillation derivatives of the volatile constituents of the carrier-oil, of less volatile distillation derivatives of the carbon bitumen, which possess the greatest solution pressure as compared with the suspending oil, and of the products of the cracking of the heavy constituents of the suspending oil and also of the heavy bitumen hydrocarbons dissolved in the suspending oil, and as well as of the products of the 20 cracking of the carbon bitumen which is insoluble in the suspending oil, which originate directly from the coal or are the result of the exchange action between the molecularly unstable gaseous-phase and the heating oil residue-phase in the 25 converter.

30. According to what is required of the heating oil products, the nature of the raw materials and the carrying out of the process may be regulated, so that it is possible to obtain, in particular cases, the finished products which have the properties 35 desired for the various cases.

One example of the invention is illustrated in the accompanying drawings, in which

40. Figure 1 shows in elevation and partial section a diagram of the entire plant for carrying out the process according to the invention.

Figure 2 shows a section on the line XX-YY of Figure 1, and

45. Figure 3 shows a vertical elevation and partial section of a modified constructional form of heater.

50. As will be seen from Figure 1, the mixture of coal, of a fineness corresponding to a 50 to 150 mesh sieve, and oil preferably prepared in a heated stirring mechanism, and stored in a receiver not shown, passes through a pipe c into a pump CP and from there through a pipe c_1 into a heat exchanger HE , where it comes into contact with the outside of the tubes. For starting and 55 shutting off the heat exchanger HE valves 21, 22 and 23 are provided.

60. From the heat exchanger HE the mixture then passes through pipes c_2 and c_3 into the chamber I of the heater CH , through which it flows at such a high speed as to be in the neighbourhood of turbulence.

65. The heater consists of three concentric heating tubes, of which the inner tube 1 serves as a gas flue, through which the exhaust gases flow in the direction of the arrow r_2 , to leave the plant through the passage SF and the chimney ST . The tube 2 is welded at its lower end to a plate s_1 , while at its upper end it is open. With the tube 70 1, the tube 3 forms at its upper end a chamber u , while at its lower end it is welded to the plate s_3 .

The result of this is that the mixture of coal and oil, after leaving the chamber I, first ascends in the annular space between the tubes 1 and 2, in counter-current to the combustion-gases flowing in the direction of the arrow r_2 , is deflected in the upper chamber u , and then falls through the annular space between the tubes 2 and 3, in counter-current to the gases flowing helically and with turbulent motion in the direction of the arrow r_1 , into the lower chamber o .

80. The cylindrical jacket s , the bottom plate s_2 and the top plate s_3 , support the brickwork CS , through which the heating element passes. In conjunction with the plate s_1 they form the admission chamber I and the discharge chamber O for the mixture of coal and oil, which are provided for cleaning purposes with manholes M_1 and M_2 .

85. The heating chamber DO provided with an oil burner FB is arranged tangentially to the heater CH . The result of this is that the gases in the annular space between the tubes 3 and 4 ascend turbulently and helically, thereby yielding a high utilization of the heat.

90. The utilization of heat and the uniform heating are also promoted by the fact that the mixture of coal and oil is introduced tangentially by the pipe c_3 into the chamber I. If in addition to this, welded-on spirals are provided in the annular spaces between the tubes 1 and 2 and 95 the tubes 2 and 3, as shown in Figure 3, the mixture of coal and oil also flows through the heating element spirally in an upward direction and in a downward direction.

95. By these measures an uneven heating, which might lead to decompositions, is prevented; deposits of coke are therefore also made impossible, and it has even been found that the particles of coal produce a scouring effect, so that by them the surfaces are polished as a mirror.

100. A separation of the gas-vapour-phase in the heating element is not possible under these circumstances. Accordingly any overheating thereof is also precluded, and a transmission of heat is obtained which is much greater than that obtained with the usual heaters.

105. The heater CH may be constructed and arranged as shown in Figure 1, or as shown in Figure 3, as a separate and independently fired heater. In the latter case there is slipped over the heating element CH a hood C_1H_1 , which, like the element CH , consists of three casings 1', 2' and 3'. By means of intermediate plates two chambers are formed, exactly as in the case of the heating element CH , namely an admission chamber I' and a discharge chamber O'. The operation carried on in this preheater is effected by passing the mixture of coal and oil first into the lower chamber I, and from this, through the heating element CH in the manner described, into the discharge chamber O, from which the mixture then passes through a connecting pipe into the admission chamber I', and from here into the heating element $C'H'$, which it leaves again by way of the discharge chamber O'.

110. In this case the heating element CH of Figure 1 would admit of being employed as a superheater for the re-introduced fixed gas phase, for the purpose of heating the latter to the temperature of molecular instability, before its entrance into the converter TST , through the piping r_3 , so that the directly fired superheater RH of Figure 1 might be omitted or kept as a reserve.

115. The superheater CH would however burn away, as will be readily understood, if it were heated

before fixed gases were available. It would therefore have to work until that moment as a steam superheater. The combustion chamber DO, already mentioned, serves for the production 5 of the heating gases by which the temperature of the mixture of coal and oil preheated in the preheater HE is brought to a temperature of from 315° to 375° C., in the heating element CH, according to the nature of the mixture and the 10 products to be obtained.

As will be gathered from Figures 1 and 2, the preheater HE is charged with hot residual oil from the converter, which flows from the residue pan 6 at the bottom of the converter, through 15 the pipe 12 into the separator Sp and from here through the pipe 13 into the pump RP, from which it is forced through the tubes of the pre-heater, which it then leaves by the pipe 14'. For the purpose of regulating the admission to this 20 preheater, valves 15, 16, 17 and 20 are provided.

The combustion chamber DO is equipped with a grating Ca, by which complete combustion is to be attained. By the fireproof material CS, on the one hand, and the fireproof covering 26, 27 25 on the other hand, a double jacket is formed with an annular space 25, through which the air entering at CA flows, for the purpose of cooling the fireproof material, whereupon it then enters, in a preheated condition, through slots provided 30 in the end wall of the combustion chamber.

The mixture of coal and oil, heated under pressure in the preheaters HE and CH up to the required dissolving temperature, passes, after leaving the heating element CH, into the pipe c4, and, after partial expansion in a reducing valve, not shown, passes tangentially into the separator D, which is interposed on the way between a lower distillation and re-action column RT and an 35 upper rectification column R₁ T₁ with a dephlegmator D₁. Now in the separator D the mixture is partially expanded, and the vapour phase separated from the liquid oil and coal phase by impact and centrifugal action. The former then ascends in the towers R₁ T₁ and D₁, in which the 40 constituents of higher boiling point are separated out, while the fractions of lower boiling point pass through the pipe V₂ into the rectifying and fractionating plant MRT₁ D₂ to be here fractionated into three finished products.

The mixture of coal and oil separated in the 45 separator D from the vapour-phase, flows, however, with the fractions flowing down and out of the towers R₁ T₁ and D₁, in a finely divided form, over the conical drip rims n₁ to n₉, in counter-current to the hot gases and vapours ascending 50 from the converter TST which enter at the bottom of the reaction tower RT through the pipe V₁. The volatile bitumen hydrocarbons contained in the suspending oil and dissolved therein are hereby vaporized and distilled off, so that a 55 vapour-phase composed of different kinds of hydrocarbons passes into the dephlegmator D₁, in which the heavier and unwanted hydrocarbons are condensed and flow back in a liquid condition by way of the towers R₁ T₁ and RT, the separator RS, the pipe t₁ and the distributor d, into the 60 converter TST.

In the converter the liquid mixture flows over the individual trays t₁ to t₂₀, which are welded to the conical central heating casing 4, which is flanged at its lower end to the outer steel casing 7, which in its turn carries at its upper end a cover 8, with the distributor d, likewise flanged. These trays are filled with metals of continuously 65 increasing melting point, upon which, as already

described in U. S. Patent No. 1,754,136, a selective building up and breaking down process takes place both in the vapour-phase located on the surface of the metal and in the liquid-phase during the downward flow of the liquid over the inclined side walls of the trays. 80

By this process, which proceeds in a hydrogenous atmosphere and under adjustable pressure conditions, at a temperature which increases from tray to tray in a downward direction, the 85 heavy hydrocarbons of the suspending oil and of the absorbed and dissolved heavy hydrocarbons of the carbon bitumen, are converted into the volatile hydrocarbons of low molecular weight of the motor fuel, which are distinguished by 90 high anti-knock properties, and the anti-knock properties of the hydrocarbons of the carbon bitumen, which are already high on account of the high carbon hydrogen ratio, are still further improved by this selective building up and breaking down process of the oil complex as a whole. 95

From the converter TST, the temperature of which is regulated by a thermostat T₁ controlling the burner FB, the gases and vapours ascend and flow in counter-current to the descending liquid 100 through the towers RT, R₁ T₁ and D₁, and flow into the rectifying and fractionating column MRT with the dephlegmator D₂, which is equipped with a thermostat regulating the water cooling so far as said gases and vapors are volatile at the temperature prevailing in the dephlegmator D₁, which may vary in different cases, and is accurately regulated by a thermostat T₂ controlling the water circulation in the dephlegmator D₁. 105

Here in the column MRT they are separated into 110 three fractions, for example, a light fraction, a medium fraction differing in volatility and a heavy fraction.

The light fraction, which is particularly suitable for operating aircraft motors, leaves the 115 dephlegmator D₂ in the form of vapour and then passes through the pipe V₃ into the coolers FC in which it is liquefied, while the permanent gases produced during the cracking process are separated in the gas separator GS and leave the plant 120 by way of the regulating valve rv, which is adjusted according to the working pressure desired in the plant. Leaving the cooler FC, the light fraction then passes through the pipe m₁ provided with a valve e₁ into the collecting tank A₁, which 125 is equipped with a gage glass g₁ and a pressure gage p₁, and from here through a valve o₁, in which it is expanded to atmospheric pressure, and through the pipe r₁ into the main reservoir.

The medium fraction, intended for ordinary 130 motors, passes through the extraction plate E of the rectifying and fractionating column MRT, into the proportional stream divider SD, from there by way of the pipe m₂ provided with the valves b₂, e₂, h₂ and h₄, into the sub-cooler DC, 135 and from there into the collecting tank A₂, with gage glass g₂ and pressure gage p₂, out of which it then flows by way of the float valve O₂, and in an expanded condition, through the pipe r₂, into the main reservoir. 140

The heavy fraction, which is suitable for Diesel-engines, flows, on the contrary, from the bottom of the fractionating column MRT through the pipe equipped with the valves b₁, h₁, h₃ and c₃ into the sub-cooler DC, and from here into the collecting 145 tank A₃, with gage glass g₃ and pressure gage p₃, out of which it passes by way of the float valve o₃ in an expanded condition, into the pipe r₃ and from there into the main reservoir.

The permanent gas, accruing in the final cooler 150

FC, flows through the gas separator GS and the pipe rg into the compressor RC. From there the excess gas is forced through the regulating valve rv into a collecting tank, not shown, from which it can be supplied, after being previously purified by being passed over activated carbon or the like, to a gasometer or to the place where it is to be used. The other part of the gas is forced through the pipe rg_2 from the compressor RC into a superheater RH, in which it is heated up to a temperature of molecular instability until it may partially decompose. It then passes out of the superheater through the pipe rg_3 and the distributor 10 into the residue pan 6, and from there into the converter TST. Since the gas inlet nozzle is welded-on tangentially to the pan, the gas entering the liquid residue sets the latter in vortex motion, until the gas itself escapes, eddying, into the annular chamber of the converter, which it traverses spirally in an upward direction, a synthetic building-up process being effected in conjunction with the molecularly unstable carbon oil phases. Since the pressure in the converter must vary according to the nature of the raw materials and the desired constitution of the ultimate products, the gas enters the converter at different pressures in different cases, these pressures being regulated by the regulating valve rv .

As already mentioned, the superheater CH, which renders continuous operation possible, may be employed as a gas heater, at least so far as a heating of the gas to a temperature of molecular instability comes into question.

If on the contrary, a rise of temperature right into the region of extensive molecular decomposition with separation of hydrogen and carbon is aimed at, the directly heated superheater RH is to be provided, two superheaters then being employed, of which one is in operation while the other is heating up. These superheaters may be equipped with a grating of firebricks, according to the air heating system known in blast furnace operation. By means of heating gases which are produced by burning gas or oil and which escape through the chimney st after leaving the superheater, the superheater is first heated to a red heat, whereupon it is hermetically sealed, and the gases are forced in by the compressor RC. When the temperature of the fireproof material is no longer high enough, a change is made to the second superheater, so that the heating period begins, whereupon this series of operations is repeated afresh. The heated gas then passes, as already described, into the residue pan and into the converter, in which case a further stabilizing colloidal distribution of the coal carbon in the residual oil is effected, a further cracking can be brought about, and the synthetic building up re-actions proceed.

The residual oil remaining in the residue pan 6, which contains about 50 per cent. by weight of colloidally distributed carbon, then flows as the finished product "Carbonol" through the pipe 12 into the separator S_p , and from there through the pipe 13 to the pump RP, which forces it through the valves 20 and 15 into the preheater HE, in which the crude mixture is preheated. From there it finally flows to a collecting tank, not shown, through the valve 16 and the pipe 14'. If, however, the residual oil flowing to the pump RP does not comply in its constitution with the requirements necessary in the finished product, it is returned through the pipe 18, the valve 19, the pipe c_4 and the re-action tower RT 75 into the converter TST, and the pan 6, to be

then led away, as a finished product complying with the requirements, through the pipe 14, and this, by suitably adjusting the valves 20 and 19, can be effected either continuously or interruptedly.

It need hardly be emphasized that the process according to the invention is in no sense limited to the treatment of the aforementioned raw materials. The apparatus for carrying it out is also not limited to the plant hereinbefore described and illustrated in the accompanying drawings.

In particular, the ash content of the fuels, which under some circumstances may be high, does not stand in the way of carrying out the process. On the contrary it has been found that the ash may under special conditions act as a catalyst accelerating the conversion. Should the presence of ash not be desired, however, it can easily be separated out at any time. If the concentrated oil and ash mixture separated out is then mixed with water, the ash becomes suspended in the water, so that it can be removed along with the water, while the separated oil remains behind and can be returned to the plant. At the same time there is produced an oil carbon residual product poor in ash, "Carbonol", which can be obtained by this refining process from a coal containing a high percentage of ash.

Through the extraction valves e_1 , e_2 and e_3 the "Bituminols" can be re-circulated into the system in a wholly or partially continuous manner for the purpose of regulating the equilibrium, or interrupted for re-conditioning purposes, by the return siphons t_2 , t_3 and t_4 , through RS and t_1 , particularly when they do not comply exactly with the requirements, in the same manner as the "Carbonol" can be re-circulated by the pump RP.

Without limiting the process to any set of indications and operating data, the following specifications are given as an illustration for the operation of the process.

Approximate analysis of a typical average bituminous coal:

	Per cent by weight
Moisture	5
Bitumen or volatile matter	35
Fixed carbon	54
Sulphur	1.2
Ash	4.8

Total 100.00

The solvent-carrier-oil may be a topped crude oil of asphaltic base, designated as a navy-fuel oil of a specific gravity: 0.875 or 30 Bé. gravity with a viscosity of 125 Saybolt seconds at 25° C. of the following fractional composition:

Distilling temperature	Distilling volume	Percent
130 to 225° C.		1.2
225 to 250° C.		5.0
250 to 275° C.		14.5
275 to 300° C.		20.0
300 to 325° C.		22.0
325 to 350° C.		30.0
Residue		5.3
Loss		2.0

At normal temperature this coal may be ground at equal ratio of coal and oil by weight in a wet-mill, which may also be heatable for the eventual reduction of the viscosity of the oil to obtain

the best results and milling-efficiency, to a fineness of from 100 to 200 mesh, or the coal may be ground dry to said fineness and be agitated into a preheated oil, or the agitator may also be heatable for proper mechanical suspension of the oil.

Since the oil has a greater wetting capacity to the coal than to the ash, a continuous operation will then produce a concentrated oil-ash-phase which can be extracted selectively from the mixture, and through treatment with hot water, this concentrated oil-ash-phase may be separated into an ash-water-phase for discard and into an oil-phase which returns to the process-cycle.

Those constituents of the ash which have potential catalytic properties however, like ferric-oxide, chrome-oxide, aluminum-chloride, etc., may be selectively separated from the oil-ash-phase and returned with the recovered oil to the process cycle as described, though it has been found, that these catalyzing constituents of the ash pass mostly over with the coal-oil-mixture.

The coal-oil-mixture is then taken from a storage-tank, which may be insulated against heat-loss, and which may have proper means to keep the coal-oil-mixture in uniform stabilization, while in intermediary storage, by the process-cycle pump and discharged under turbulent flow through the preheating heat-exchanging devices of the process, by cooling thereby the extracted products, like "Barbonol" as shown in the drawings, and is then heated in thin-layer double-heated, turbulent, counter-current flow to the heating medium, which may also be indirectly heated, to a digesting temperature of 300° to 350° C. under a self-generated pump-pressure in the system of from 7 kg. to 15 kg. or 125 to 225 lbs. per square inch.

After having reached said temperature under rapid turbulent flow, the mixture should be kept under said predigesting temperatures of from 15 to 30 minutes, by allowing the mixture, after leaving the rapid turbulent heater to flow through so-called digesting or soaking tubes, in which the turbulent flow is kept up, which tubes are to be protected against heat-loss by either placing them into a flue through which pass waste-gases of a temperature from 260° to 371° C., or by proper heat-insulations which are not shown in the drawings for simplicity's sake.

The thus pre-digested coal-oil-mixture is now discharged under concomitant pressure drop of from 50 to 100 lbs. (3.35 kg. to 6.7 kg. into a centrifugal impact separator midways the fractionation or rectification tower and the down-filming reaction-tower, for the separation of the vapor-phase from the liquid coal-oil-phase, produced through the pre-digesting heating and the pressure-drop, causing rapid vaporization and distillation as described in the application.

The residual coal-oil-phase plus the reflux-phase from the dephlegmator of the fractionating column now passes downward by filming gravity flow over the reaction-tower to the solvent-distilling-cracking converter of the process, where the temperature is progressively and stepwise increased to between 400° C. and 450° C.

The coal-oil-mixture undergoing subsequently and alternatively solvent, distilling and cracking steps with disintegrating and integrating conversion steps produced by the reactive interaction of the re-cycled hydrogenous gas-phase which has been heated on its return cycle to the process to a temperature of molecular instability and partial decomposition, reaching temperatures of from 500° to 600° C.

The sulphur-phase of the coal will only partly pass over with the gas-vapor-phase, where it may be eliminated by scrubbing the residual gases with caustic soda or the like, whereas the greatest part of the sulphur will stay with the dispersed coal in the "Barbonol." If the coal allows a total recovery of 30% of the total 35% bitumen-content, according to the analysis of the coal, then the carrier-solvent-oil-phase may be converted into "bituminous" to the extent of: 30 plus 5% moisture, plus 3% ash, plus 0.4% sulphur=38.4% or approximately 39 to 40%, by weight, equal to approximately 50%, by volume, of the original carrier-oil, if the residual coal-oil-phase, as "Barbonol" is to be composed of approximately 50%, by weight, of colloidal carbon and of 50%, by weight, of oil.

The coal-oil-ratio, by weight, of the original mixture to be converted may therefore change between considerable limits up and down, as illustrated on this particular specific coal-oil-mixture, according to the specific composition of the primary material, forming the charging-stock, for which consideration, only the analysis of the coal and the oil used are the deciding factors in which proportion they can be mixed, depending in addition upon the chemical nature of the relative components.

Due to the complexity of the materials for the charging stock, the temperature, pressures, pressure-drop, ratios of coal and oil-mixtures are subject to wide variations, and can only be determined by laboratory tests and operating experience, based on averaging conditions and under the influence of the mass-reaction factors, which are only disclosed in industrial application.

Having now particularly described and ascertained the nature of said invention, and in what manner the same is to be performed, I declare that what I claim is:—

1. A process for simultaneous distillation of liquid and solid hydrocarbons of the type of mineral oil and coal, which consists in forming an emulsion of coal-dust and oil, preheating the emulsion under agitation, then gradually heating the emulsion under pressure to a temperature sufficient to volatilize the most volatile constituents when the pressure is reduced, then separating under reduced pressure the more volatile constituents from the liquid mixture, further heating the residual constituents of said mixture at gradually increasing temperatures to convert said constituents into lower boiling constituents, separating the vapors and finally rectifying and liquefying said vapors, thereby producing liquid fuel of different grades.

2. A process as in claim 1 in which the gradual heating of the emulsion is conducted in thin, concentric, annular zones and is passed in thin films in said zones countercurrently to a heating medium.

3. A process as in claim 1 in which the preheated emulsion is introduced tangentially into the zone of admission.

4. A process as in claim 1 in which combustion gas for heating said zones is led in a helical path around the zones.

5. A process as in claim 1 in which the residual constituents of the emulsion are re-circulated in the process after the separation of the more volatile vapors, and brought in contact with metals of different and gradually increasing temperatures.

6. An apparatus for production of motor fuel from a mixture of liquid and solid hydrocarbons, comprising a preheater for said mixture adapted

to make an emulsion thereof, a secondary heater consisting of concentric cylinders forming between them thin, annular zones connected in series, means for delivering said emulsion into the inner zone, helical elements in said zones adapted to create a helical flow of the emulsion through said zones, and means for introducing heating gas for indirect heat exchange with materials in said zones and for passing said gas in a helical path countercurrent to the flow of the emulsion.

7. An apparatus for production of motor fuel from a mixture of liquid and solid hydrocarbons, comprising a heater provided with concentric tubular members forming between them thin, annu-

lar zones connected in series, means for delivering said mixture in the form of an emulsion to the first of said zones, means for introducing heating gas for indirect heat exchange with said emulsion in the zones, superimposed trays exterior to said tubular members within the heater, said trays containing metals of different melting points, and means for recirculating the residual constituents of the emulsion after separation of the more volatile vapors, thereby causing said residual constituents to contact with said metals in their order from the lower to the higher melting points.
